United States Patent Office

Des. 211,648
Patented July 9, 1968

211,648

DOLL OR THE LIKE

William A. Peck, Lee E. Blom, and Frederick A. Beebe, Baltimore, Md., assignors to Leon Shaffer Golnick Advertising, Inc., Baltimore, Md., a corporation of Maryland

Filed May 1, 1967, Ser. No. 6,889

Term of patent 14 years

(Cl. D34—4)

FIG. 5.

FIG. 2.

FIG. 1.

FIG. 3.

FIG. 4.

FIG. 6.

FIG. 1 is a front elevational view of a doll showing our new design;

FIG. 2 is a side elevational view thereof;

FIG. 3 is a side elevational view opposite that of FIG. 2;

FIG. 4 is an elevational view from the rear;

FIG. 5 is a top plan view; and

FIG. 6 is a bottom plan view.

We claim:

The design for a doll or the like, substantially as shown.
